UNITED STATES PATENT OFFICE.

GEORGE S. BRIGGS, OF ROCKFORD, ILLINOIS, ASSIGNOR TO THE L. A. WEY-BURN COMPANY, OF SAME PLACE.

MECHANISM FOR MAKING SHARES FOR LISTING-PLOWS.

SPECIFICATION forming part of Letters Patent No. 412,320, dated October 8, 1889.

Application filed November 10, 1887. Serial No. 254,838. (No model.)

To all whom it may concern:

Be it known that I, GEORGE S. BRIGGS, a citizen of the United States, residing at Rockford, in the county of Winnebago and State 5 of Illinois, have invented certain new and useful Improvements in Machines for Manufacturing Shares for Listing-Plows, of which the following is a specification.

The object of this invention is to produce 10 machines for manufacturing shares for listing-plows with less waste of material than heretofore.

This invention consists, essentially, of improved dies and die-supports for forming 15 blanks into shares.

Referring to the accompanying drawings, which form a part of this specification, Figure 1 is a female-die base and anvil. Fig. 2 is a male-die drop and hammer. Fig. 3 is a 20 vertical section through the dotted line $x-x$ of Fig. 2 of the die-base, anvil, drop, and hammer just mentioned, in operative relation. Fig. 4 is a male spreading-die. Figs. 5, 6, 7, 8, and 9 are respectively views of share-blanks 25 in different stages of manufacture and a share, all of which will be fully described herein-after.

Like letters of reference indicate corresponding parts throughout the several views.

A represents a die-block, of any suitable 30 form and construction.

A' represents a die-section, which may be integral with the base A or not, as desired.

A² represents a combined drop-stop and 35 anvil.

A³ represents a vertical strengthening-rib, for strengthening the parts A A², which is shown only in Fig. 3.

B represents a die-block, of any suitable 40 form and construction.

B' represents a detachable interchangeable upsetting-die section secured to the drop B by means of the bolts B².

B³ represents a combined hammer and drop- 45 stop, which, in conjunction with the combined stop and anvil A², serves both to straighten share-blanks that have been warped by upsetting and spreading the same, and to stop the die-block B and any die secured thereto 50 at the required distance from the die-section A'.

C represents a detachable spreading-die section, which is interchangeable with the upsetting-die section B', as indicated by the dotted lines x' x' in Fig. 2.

55

D represents a listing-plow share-blank of the form ordinarily used for manufacturing listing-plow shares.

E represents a listing-plow share-blank of substantially the form employed in manufacturing listing-plow shares with my improved machine.

It may be seen by an inspection and comparison of the two forms just referred to that the V-shaped notch E' in the heel of the blank 65 E is about one-third smaller than the corresponding notch D' in the heel of the share-blank D, that the distance between the points E² of the share-blank E is considerably less than the corresponding distance between the 70 points D² of the share-blank D, and that the portions E³ that have been cut from the blank E are of less dimensions than the corresponding portions D³ that have been cut from the blank D.

75 It will be found in practice that a saving of about one-third may be realized in the amount of material required to manufacture listing-plow shares by cutting the blanks for the same of substantially the form and proportions 80 shown in Fig. 5, and afterward subjecting them to the following process:

In order to manufacture a listing-plow share most advantageously with my machine, I take a share-blank of substantially the form and 85 proportions represented by E in Fig. 5, and heat the V-shaped portion thereof until plastic enough to readily yield to hammer-strokes. I next place the blank, point downward, into the die-section A', and cause the die-block B, 90 with its upsetting-die section B', to descend, whereupon the inner portion of the V-shaped notch in the blank will have been upset, as shown by the notch F' in the blank F, Fig. 6. Having substituted the spreading-die section 95 C for the upsetting-die section B', reheat the upset share-blank F and replace it in the die-section A', and allow the die-block B, with its spreading-die section C, to descend upon the same, whereupon the upset share-blank will 100 have been spread and made to assume the form D. (Shown in Fig. 8.)

G, Fig. 7, represents the blank F after being upset and spread, as above described, and having the edges G' thereof thinned by heating and hammering the same.

5 Fig. 9 shows a completed listing-plow share, formed from the upset and spread share-blank G, after having its edges G' thinned and trimmed and having been shaped in shaping-dies.

10 It is necessary to upset the V-shaped notch, especially the inner portion thereof, in the heel of a share-blank, in order to mass together the requisite amount of material to be spread into a full-width blank.

15 If the inner portion of the notch in any share-blank is not sufficiently upset before the share is subjected to the operation of

spreading, the portions of the share adjacent thereto will thereby become attenuated to such a degree as to render the blank unfit for 20 use in making a share.

I claim—

The herein-described mechanism for shaping blanks for shares of listing-plows, consisting of a die-block A, provided with the die-section A', the die-block B, and the interchangeable upsetting and spreading die sections B' and C, all constructed and to be operated substantially as described. 25

GEORGE S. BRIGGS.
